UNITED STATES PATENT OFFICE

HERMAN C. BOHNET, OF LANSING, MICHIGAN

VENTILATED STOP SIGNAL CASING

Application filed February 16, 1931. Serial No. 516,122.

Practically all stop or traffic signals are operated by electrical current either for use of light bulbs, carbon arcing lights, motors or other electrical devices, all of which are usually encased in metal or other containers to protect them from the elements. It is a known fact that light bulbs and motors generate excessive heat while in use, the heat being greatly increased when placed in enclosures, in fact, sufficient to greatly reduce the life of their usefulness, further that while ventilating tubes or air ducts are provided, such openings usually permit dust to enter and accumulate on the lens, bulbs and other mechanism to such an extent that periodical inspection and cleaning operations are necessary to insure clear and effective signal devices. It may, therefore, be considered the objects of my present invention to provide means of changing or replacing the stagnant hot air inside the enclosure with fresh air other than by gravity intake, and to overcome the accumulation of dust within the enclosure that enter through port holes or other openings while the signal is in operation, without impairing ventilation.

To the attainment of the foregoing the invention consists in the improvement herein-after described and definitely claimed.

30 In the drawing:

Figure 1 is an approximately central vertical longitudinal sectional view through a traffic signal in accordance with this invention.

35 Figure 2 is a sectional view approximately on the line 2—2 of Figure 1, looking in the direction of the arrows.

The signal housing or casing 1 carries the usual signals and these signals are operated 40 in the usual manner by an electric motor generator 2. The housing 1, adjacent to its top and above the signal lamps, is provided with a continuous series of spaced air ports or ventilating openings 3 and is likewise provided with a second series of such openings 4 arranged between the bottom or base 5 and the false bottom 6' of the casing 1. On the shaft of the motor I secure the hub of a suction fan 6. The fan is arranged in a housing 7. The face of the housing in which the

fan is received is open and the bottom of the housing is formed with an extension 8 that passes through an opening in the false bottom 6' of the casing or housing 1 and is secured to the said false bottom.

The suction fan is rotated when the motor is in operation to operate the signals and the turning of the suction fan will draw air through the ports 4. These ports may be covered by a mesh disc 9, although the employment of such discs is not an absolute requirement, and for the sake of illustration I have disclosed only one of such discs in Figure 1 of the drawing. The outside air is drawn by the fan through the housing 1 and is directed against the motor to prevent dust accumulating thereon and for retaining the motor in a clean condition. The air is caused to circulate entirely around the inside of the casing 1 and will find an outlet through the outer ports 3. The air thus circulated will eject any dust from the casing or from any of the parts of the signal operating mechanism therein. The regulation of the air necessary to cool and retain the parts on the interior of the casing 1 in a clean condition is to be governed by the size of the suction fan required. The rush of air created will be sufficient to eject or hold out all dust that would otherwise find its way through ordinary vent openings.

Having described the invention, I claim:

A means for circulating air and ejecting dust and dirt from a housing that has mechanism therein operated by an electric motor and in which the housing is provided with an upper and lower series of air ports and with a false bottom arranged above the lower series of ports and upon which the motor rests and a suction fan driven by the shaft of the motor, comprising a hollow angle member in whose horizontal branch the suction fan is received and whose vertical branch is secured to the false bottom and communicates with the space between said false bottom and the bottom of the housing.

In testimony whereof I affix my signature.

HERMAN C. BOHNET.
